UNITED STATES PATENT OFFICE.

WILLIAM S. POINDEXTER, OF BRIDGEPORT, ILLINOIS.

PUMPING-JACK.

1,162,509.

Specification of Letters Patent. Patented Nov. 30, 1915.

Application filed June 17, 1915. Serial No. 34,684.

To all whom it may concern:

Be it known that I, WILLIAM S. POINDEXTER, a citizen of the United States, residing at Bridgeport, in the county of Lawrence and State of Illinois, have invented certain new and useful Improvements in Pumping-Jacks; and I do declare the following to be a full, clear, and exact description of the invention, such as will enable others skilled in the art to which it appertains to make and use the same.

My invention relates to improvements in pumping jacks and more particularly to those primarily designed for use in connection with oil well pumps, although the device need not be limited to this one application.

The object of the invention is to improve upon the general construction of devices of the class set forth to such an extent as to provide an extremely simple and inexpensive jack, yet one which will be efficient and durable and will possess a number of highly advantageous features.

To this end, the invention resides in certain novel features of construction and in the unique combinations of parts herein-after fully described and claimed.

In describing the device, I shall refer to the accompanying drawings wherein like reference characters designate corresponding parts throughout the several views and wherein:

Figure 1 is a side elevation of a jack constructed in accordance with my invention; Fig. 2 is a rear end view thereof; Fig. 3 is a vertical longitudinal section as seen on the plane indicated by the line 3—3 of Fig. 2; Figs. 4 and 5 are detail vertical transverse sections as seen on the planes indicated by the lines 4—4, 5—5 of Fig. 1; Figs. 6, 7 and 8 are detail perspective views of portions of the several couplings to be described; and Fig. 9 is a similar view of the bearing block.

In these drawings which constitute a part of the application, the numeral 1 indicates a sleeper, preferably of cylindrical formation, which is secured against movement by spikes or the like 2, the upper side of the sleeper receiving thereon a pair of arcuate supporting feet 3 carried by the lower ends of a pair of upwardly converging standards 4 whose upper ends are preferably flattened, a shaft 5, in the form of a bolt, being passed through said flattened upper ends and through a right angular coupling member 6

interposed therebetween. The opposite ends of the shaft 5 project beyond the standards and are received by eyes 7 on the ends of guy cables 8 which lead rearwardly to a suitable anchor (not shown).

The coupling member 6 comprises two right angular cast metal plates 9 disposed side by side and secured in contact with each other by bolts 10, the abutting faces 65 of said plates 9 being provided with pairs of horizontally disposed registering grooves 11 which constitute seats for a pair of forwardly extending horizontal bars 12, said bars being preferably of tubular formation 70 for the sake of lightness. In addition to the grooves 11, the aforesaid abutting faces of the two plates 9 are provided with additional pairs of vertically disposed registering grooves 13 which likewise constitute 75 seats, these seats receiving therein the upper ends of a pair of vertically disposed parallel bars 14 which are likewise preferably in the form of tubes, two of the bolts 10 being passed through the portions of the bars 14 80 confined in the seats thereof, while the other bolts 10 intercept the seats formed by the grooves 11 and pass through the rear ends of the bars 12 therein. By this construction, the bolts in question not only secure 85 the two sections or plates 9 in contact with each other and in binding frictional contact with the bars 12 and 14, but they positively prevent removal of said bars.

The opening 15 in the coupling member 90 6 through which the shaft 5 passes, may or may not be equipped with a bushing, but the same is preferable for reasons well known to those skilled in the art to which the invention relates. Since practically all 95 wear is exerted upon substantially the upper side of the opening 15, such side is preferably formed by a poly-sided bushing 16 received in a groove which communicates with said opening as clearly shown in Figs. 100 4 and 7.

Disposed at the lower ends of the two upright bars 14 and having seats 13^a receiving said ends therein, is a two-part coupling member 6^a constructed in practically the 105 same manner as the member 6 previously described, said member 6^a being also provided with a pair of parallel seats 11^a which although corresponding to the seats formed by the grooves 11, incline upwardly 110 and forwardly as clearly shown in the several figures of the drawings. The seats 11^a

receive therein the lower ends of a pair of upwardly and forwardly inclining tubular bars 17 whose upper ends are secured within downwardly and rearwardly inclined 5 seats 13^b formed in a third coupling member 6^b which, like the members 6 and 6^a is formed in two sections bolted together, and is provided with horizontally disposed seats 11^b corresponding to those seen at 11 and 10 11^a and receiving the front ends of the bars 12. It will be noted by reference to the drawings, that bolts 10 not only intercept the seats of the couplings 6, but those with which the coupling members 6^a and 6^b are 15 provided, whereby the corners of the entire triangular frame formed by the pipes 12, 14 and 17, are rigidly connected.

Disposed respectively above the coupling member 6^b and in rear of the member 6^a are 20 the transverse shafts 23 and 18, the latter being connected to the reciprocatory rods 19 which, when actuated, oscillate the triangular frame in such a manner as to cause its upper front corner to move vertically, thereby reciprocating the piston rod 20 of the pump 21 in the necessary manner, connection being established between the rod 20 and the shaft 23 by upright links 22 which depend from said shaft and are pivoted at 25 their lower ends to a cross head or the like 30 24 carried by said piston rod.

The shafts 18 and 23 are each received by one of a pair of transverse bearing grooves 25 formed in the two identical bearing 35 blocks 26 having on one side undercut tongues 27 which are received in grooves existing between pairs of parallel undercut ribs 28 which project from and are formed integrally with the two sections of the members 6^a and 6^b, removal of the blocks 26 being normally prevented by practically any preferred means such for instance as the set screws 29 threaded through the blocks 26 and into contact with the aforesaid members. By this detail of construction it will 40 be evident that when one of the grooves 25 becomes worn, it is simply necessary to remove the shaft therefrom, reverse the bear- 45

ing block 26 and dispose said shaft in the unworn groove. Furthermore the leverage 50 of the jack and the length of the stroke thereof may be varied by this construction.

From the foregoing description, taken in connection with the accompanying drawings, it will be evident that although comparatively simple and inexpensive construction has been provided for the attainment of the desired end, the complete device will be highly efficient and durable.

In the drawings, certain specific details of 60 construction have been shown for accomplishing probably the best results, and in the preceding such details have been described, but it will be evident that I need not be limited thereto otherwise than to the extent to which the appended claims restrict me.

I claim:

1. A pumping jack comprising a pivotally mounted angular frame having at one of its 70 angles a coupling formed of two parts clamped together, and a bearing having a tongue clamped between the aforesaid parts of the coupling, a reciprocatory member having a pivotal connection with said bearing, and an additional reciprocatory member connected to one of the other angles of the frame.

2. A pumping jack comprising a pivotally mounted angular frame having at one of its 80 angles a coupling formed of two parts clamped together, a pair of parallel undercut ribs carried one by each part of the coupling, a bearing having an angular tongue clamped between said ribs, a reciprocatory 85 member having a pivotal connection with said bearing, and an additional reciprocatory member pivotally connected to one of the other angles of the frame.

In testimony whereof I have hereunto set 90 my hand in presence of two subscribing witnesses.

WILLIAM S. POINDEXTER.
